Primary Examiner — Leanne Was-Englehart

CLAIM

The ornamental design for a fender flare, as shown and described.

DESCRIPTION

FIG. 1 is a front perspective view of a fender flare;
FIG. 2 is a bottom rear perspective view thereof;
FIG. 3 is a front elevational view thereof;
FIG. 4 is a rear elevational view thereof;
FIG. 5 is a left elevational view thereof;
FIG. 6 is a right elevational view thereof;
FIG. 7 is a top plan view thereof;
FIG. 8 is a bottom plan view thereof; and,
FIG. 9 is an enlarged view of a portion of the fender flare of FIG. 1 shown in area designated FIG. 9 in FIG. 1.
The bottom surface and the internal structure on the rear, shown in broken lines, forms no part of the claimed design.
